ADJUSTABLE HEAD BAND

Frederick M. Bowers, Chester, Pa.

Application October 1, 1937, Serial No. 166,795

3 Claims.

(Cl. 2-8)

This invention relates to head bands such as are commonly employed in conjunction with welding helmets and similar protective devices for the purpose of supporting the helmet in position 5 on the head of the wearer.

At the present time it is common practice in the art of welding helmets to employ a head band of the character above identified which is adjustable so as to provide a proper fit with the 10 head of the wearer. However, known devices of this character are not meeting with complete approval in that considerable difficulty and inconvenience is experienced in obtaining the required adjustment.

Accordingly this invention has in view, as its 15 foremost objective, the provision of an adjustable head band of the character above noted which is automatically and easily adjusted to the size of the head of the wearer. In carrying out this objective in a practical embodiment this invention 20 contemplates an arrangement wherein the head band consists of a strip of material designed to encompass the head of the wearer, and which strip has a pair of free ends that are relatively 25 movable to provide the required adjustment.

In accordance with the present invention these 30 ends are received in a casing that is disposed about the free ends of the strip, and yieldable means is associated with the free ends to constantly exert a tendency drawing these ends together. However, this yieldable means may be overcome to spread the ends apart as occasion 35 demands.

In this connection a particularly important 40 feature of the invention is tied up with the presence of this yieldable means which preferably will take the form of a light tension coil spring. With the head band disposed about the head of the wearer, and the spring exerting a tendency to pull the free extremities together, a good grip by the band on the wearer's head is assured, and at the same time the light tension in the spring does not materially interfere with the comfort with 45 which the band may be worn.

Another somewhat more detailed object of the 50 invention is the provision of an adjustable head band of the character above described in which means is included for limiting the amount of movement of the free extremities of the strip with respect to the casing in which they are received. This object of the invention is achieved by availing of a flattened-out tubular member as 55 the casing element, and one side of the flattened-out tubular member is formed with a slot. The free extremities of the strip are snugly received

in the slot, and protuberances are placed on the free ends of the strip in the slot, and each protuberance performs two functions. In the first instance they constitute a means for anchoring the extremities of the coil spring to the free extremities of the strip, and by cooperating with the end walls of the slot they constitute the means for limiting movement of the free extremities of the strip with respect to the casing. 5

Various other more detailed objects and advantages of the invention will in part become apparent and in part be hereinafter stated. 10

The invention, therefore, comprises an adjustable head band of the character above described in which a strip of material constituting the head band is arranged with a pair of free extremities that are relatively movable to provide the required adjustment. These free extremities are disposed in a casing consisting of a flattened-out 15 tubular member which snugly receives the free ends, and a flat wall of the casing is provided with a slot. Each end portion adjacent a free extremity of the strip is provided with a protuberance that cooperates with the ends of the slot to constitute a stop, and a coil spring is anchored 20 at each end to these protuberances. This coil spring constantly exerts a tendency to draw the 25 free ends towards each other.

For a full and more complete understanding of the invention reference may be had to the following 30 description and accompanying drawing, wherein

Figure 1 is a perspective view of a head band which is rendered adjustable in accordance with the precepts of this invention. 35

Figure 2 is a horizontal sectional showing taken through the casing and the free ends of the strip which constitute the adjustable feature, and 35

Figure 3 is a side elevational showing taken about on a plane at right-angles to the showing 40 of Figure 2.

At this point it is well to note that an adjustable head band may be made with only one adjustable connection, as above outlined, or may be designed to include two or more of these adjustable connections. When two or more adjustable connections are employed it is possible to maintain the condition of light tension on the springs, and thus insure of a comfortable wearing of the head band; this being particularly true when a 45 wide variation in the adjustment which is possible is desired. 50

Following this thought, the head band which is 55 illustrated in Figure 1 and referred to in its entirety by the reference character B is shown as

including two of the adjustable connections, each being referred to in its entirety at C and D respectively. In this embodiment of the invention the head band B comprises side strips 10 and 11 each of which has free ends that constitute part 5 of the adjustable connections C and D. Inasmuch as the adjustable connections C and D are identical, only one of them will be here described for the purpose of this specification.

10 Ordinarily the head band B includes a top cross piece 13 that is anchored at each end to the side strips 10 and 11 respectively, as indicated at 14 and 15. This cross piece 13 may also include turned-back portions 16 on which is pivotally mounted the welding helmet (not illustrated).

15 It is notable that each of the strips 10, 11, and 13 may be made from any suitable material, although the invention has particularly in mind the use of a fibrous material that is particularly 20 adapted to the manufacturing operations which result in the formation of the finished article that has the desired properties of strength and rigidity.

25 Referring now more particularly to Figures 2 and 3, a free end of each of the strips 10 and 11 is shown as being received in a casing 17. This casing 17 preferably takes the form of a flattened-out tubular element which snugly encompasses the strips 10 and 11 adjacent their free ends. 30 This casing 17 is curved to conform to the curvature of the corresponding portion of a wearer's head, and the outer flattened wall thereof is designated 18. This wall 18 is shown as formed with a slot 19 having curved end walls 20.

35 Protuberances such as the eyelets shown at 21 are carried by the strips 10 and 11 adjacent their free ends, and project up into the slot 19. Relative movement of the strip 10 with respect to the casing 17 is limited by the end wall 20 of the slot 19 and the protuberance 21 which is adapted 40 to engage thereagainst, and in a similar manner relative movement of the strip 11 with respect to the casing 17 is limited by the corresponding end wall 20 of the slot 19 and the protuberance 45 21 that is carried by the strip 11.

A light tension coil spring shown at 22 is anchored at each end to the eyelets 21, and this spring 22 normally exerts a tendency drawing the free ends of the strips 10 and 11 together. 50 However, it is obvious that the strips 10 and 11 may be spread apart against the influence of the spring 22.

55 When the adjustable head band hereinbefore described is to be placed on the head of the wearer, sufficient force is applied to enlarge the complete head band, as defined by side pieces 10 and 11, and the casings 17 of the connections C and D, to clear the head of the wearer. Upon this force being released the springs 22 and the 60 connections C and D will tighten the strips 10 and 11 to cause a snug fit about the head of the wearer.

While a preferred specific embodiment of the invention is hereinbefore set forth it is to be clearly understood that I am not to be limited to the exact construction illustrated and described, because various modifications of these 5 details may be provided in putting the invention into practice within the purview of the appended claims.

I claim:

1. In an adjustable head band for welding helmets and the like, an adjustable connection for the head band comprising a casing that is curved to conform generally to the curvature of the head of a wearer, said casing having an outer wall formed with a slot, side strips of the head band 15 extending into and snugly received in said casing and having free ends in the casing which are relatively movable, each side strip being provided with a protuberance adjacent to its free end, and which protuberance extends into the 20 slot, and yieldable means constantly exerting a tendency to draw the free ends of the strips together.

2. In an adjustable head band for welding helmets and the like, an adjustable connection for 25 the head band comprising a casing that is curved to conform generally to the curvature of the head of a wearer, said casing having an outer wall formed with a slot, side strips of the head band 30 extending into and snugly received in said casing and having free ends in the casing which are relatively movable, each side strip being provided with a protuberance adjacent to its free end, and which protuberance extends into the slot, and a coil spring having one end anchored 35 to the protuberance on one strip and another end anchored to the protuberance on the other strip, said coil spring being of light tension and exerting a tendency to draw the free ends of said strips together.

40 3. An adjustable head band of the character described comprising a pair of side strips having free extremities, the adjacent extremities of each side strip being connected by an adjustable connection, each of said adjustable connections 45 consisting of a casing that snugly receives the portions of the side strips adjacent the free ends thereof, said casing being a flattened-out tubular element that is curved to conform generally to the curvature of the head of a wearer, the outer 50 wall of said casing being formed with a slot, a protuberance carried by each side strip adjacent its free end and projecting into said slot, each protuberance being adapted to cooperate with an extremity of the said slot to constitute a stop, 55 and a coil spring having one end anchored to the protuberance on one side strip and the other end anchored to the protuberance on the other side strip.

FREDERICK M. BOWERS. 60
